ANTON HAEUPEL AND JOHN REINHARDT, OF PHILADELPHIA, PENNSYLVANIA.

Letters Patent No. 79,841, dated June 30, 1868; antedated June 18, 1868.

IMPROVEMENT IN LOCOMOTIVE STEAM-ENGINES.

The Schedule referred to in these Letters Patent and making part of the same.

TO ALL WHOM IT MAY CONCERN:

Be it known that we, ANTON HAEUPEL and JOHN REINHARDT, both of the city and county of Philadelphia, and State of Pennsylvania, have invented a new and useful Improvement in Steam-Engines; and we do hereby declare the following to be a full, clear, and exact description of the same, reference being had to the accompanying drawings, which are made a part of this specification.

The subject of this invention is a steam-engine in which the stroke of the valves is made variable by means of a wheel, which is adjustably mounted upon the driving-shaft, and which actuates the connections through which motion is imparted to the valve-rods.

The accompanying drawings represent our invention as applied to a locomotive steam-engine, of which—

Figure 1 is a horizontal section, presenting a top view of the shaded parts of fig. 2.

Figure 2 is a side elevation, the near driving-wheel and a portion of the frame being removed.

Figure 3 is a detached plan view of a portion of the driving-shaft, and a horizontal sectional view of the attached valve-driving wheel and appurtenances thereof, the plane of section being shown by the line $y-y$, fig. 4.

Figure 4 is a sectional elevation of the parts shown in fig. 3, the plane of section being indicated by the lines $x-x$.

Similar letters of reference indicate corresponding parts in the several figures.

A may represent the boiler of a locomotive-engine; B, the fire-box; C C, the driving-wheels upon the main shaft D, and E E the leading-wheels. F F are the cylinders, and G G the steam-regulating slide-valves, the boxes, G', of the latter surmounting the cylinders in customary manner. The piston-rods F' F' are connected to the driving-wheels C C in the ordinary way. As the valve-connections, or the parts more directly concerned in operating the valves, constitute the subject of our invention, we will confine the ensuing description thereto, it being of course understood that the other parts of the machinery are merely represented by way of affording a complete illustration of a mode of carrying the invention into effect.

Each valve-rod, H, is suitably jointed to a rocking-elbow lever, I, turning on a vertical spindle or axis on the frame, and the two levers, I I, are connected by the rods J J, respectively, with the vibrating-levers K K. The end of each lever K is formed with a jaw or opening, k, fig. 3, which receives a knob or cylindrical projection, l, on a reciprocating slide, L. These slides L are arranged as shown in fig. 1, the one being at the top and the other at the front of the wheel or disk M, upon the main shaft D. Each slide L carries a pair of friction-rollers, L' L', working at the opposite sides of and in contact with the transversely circular rim of the wheel M. The wheel M being held in an oblique position upon the shaft D, serves, when rotating, to impart a vibrating motion to the levers K K, through the medium of the wheels L' L' and reciprocating slides L L; and said levers K K transmit the desired movement to the valves G G, through the connections J I H. It is obvious that the deviation of the wheel M from a plane at right angles to the axis of the shaft D determines the stroke and the velocity of the slides L, and consequently of the valves G. In order to vary the degree of obliquity of the wheel M, and hence to change the stroke of the valves to any desired extent, we have provided means for adjusting said wheel and locking it in the desired working position, as we will now describe.

$m m$ (see figs. 3 and 4) are screws passing through the hub of wheel M at diametrically opposite points, and into apertures at opposite points on the shaft D, as shown in fig. 3. These screws $m m$, while causing the wheel M to rotate with the shaft D, form centres upon which said wheel, when not otherwise held, may be turned to any degree of obliquity in relation to the shaft D. The wheel M is locked in position, released, and adjusted by the engineer or other attendant, by means of the lever N and trigger O, which are respectively connected with the sliding collars Q and P on the shaft D. While the collars P and Q may be slid endways on the shaft D, they are caused to rotate with said shaft by the spline d. The collars P and Q are formed with circumferential grooves, p q, fig. 3, in which rest forks n o, which vibrate upon vertical pivots or axes at $n^1 o^1$. The fork n is connected to the lever N by means of the rods $n^2 n^3$ and lever n^4 . The fork o is connected to the trigger O by the rods $o^2 o^3 o^4$ and lever o^5 .

The wheel M is connected to the collar P by means of an arm, R, jointed or pivoted at both its points of attachment. When the collar P is locked so as to be held against endwise movement upon the shaft D, the arm R holds the wheel M rigidly in position, and thus maintains the obliquity of position under which the wheel is to operate. The collar P is held against endwise movement by the engagement of the key S with one of the notches d' , (see fig. 3,) but when it is desired to give the wheel M a new position, in order to change the stroke of the valve as aforesaid, the key S may be withdrawn from the notch d' by retracting the collar Q, or, in other words, drawing the same away from the collar P, thereby causing the oblique end of the bar T, which is made fast to said collar Q, to act upon the key S, and disengage it from the notch in the shaft. The key S having been disengaged from the shaft D by pressure upon the trigger O, both the trigger and lever N are pushed or pulled simultaneously so as to move the collars from or toward the wheel M, and thus turn said wheel into the desired position. When releasing the lever N and trigger O, the latter is actuated by the spring n' , and the consequent movement of the collar Q and oblique-ended bar T, replaces the key S in one of the notches, d' , and thus locks the wheel M in its new position, the lever N being held immovably by the engagement of the dog n' with the stationary rack U.

Having thus described our invention, what we claim as new herein, and desire to secure by Letters Patent, is—

1. A valve-regulating wheel or disk, M, in combination with the shaft D, having notches, d' , movable collars P Q, key S, and bar T, all arranged and operating substantially as herein set forth.
2. The combination, with the movable collars P Q, of the releasing-trigger O, lever N, and forks $n\ o$, with their described connections, substantially as herein set forth.
3. The slides L L, friction-rollers L¹ L², and vibrating-levers K K, in combination with the wheel M, for communicating motion to the valves, substantially as described.

To the above specification of our improvement in steam-engines, we have signed our hands, this 25th day of October, 1867.

ANTON HAEUPEL,
JOHN REINHARDT.
